DATA TRANSCRIBER

Eugene W. Yeager, Lansdale, Pa., assignor to Digital Information Devices, Inc., Norristown, Pa., a corporation of Delaware

Filed Feb. 4, 1969, Ser. No. 15,619
216,985

Term of patent 14 years

Int. Cl. D14—02

U.S. Cl. D26—5

FIG. 1.

FIG. 2.

FIG. 3.

FIG. 4.

FIG. 5.

FIG. 1 is a perspective view from the front to one side and above the data transcriber;

FIG. 2 is a perspective view from the back and opposite side from that viewed in FIG 1 and below the data transcriber;

FIG. 3 is a top plan view from above the data transcriber;

FIG. 4 is an elevational view from the front of the data transcriber;

FIG. 5 is an elevational view from one side of the data transcriber; and

FIG. 6 is a side elevational view from the other side of the data transcriber.

I claim:

The ornamental design for a data transcriber, substantially as shown.
